(57) **CLAIM**

The ornamental design for a headlight, as shown and described.

DESCRIPTION

FIG. 1 is a view of a first embodiment of our new design taken from the front and right side thereof, a vehicle in which the headlight is installed being shown in broken lines for illustrative purposes only;

FIG. 2 is a front elevation view of a right headlight showing a first embodiment of our new design and;

FIG. 3 is a front elevation view of a right headlight showing a second embodiment of our new design, wherein the only difference resides in the shape of the claimed design.
